WELL PUMPING APPARATUS

Loyd E. Hutchison, Houston, Tex.

Application October 15, 1934, Serial No. 748,359

10 Claims. (Cl. 60—52)

This invention relates to a well pumping apparatus.

An object of the invention is to provide an apparatus of the character described to be used for pumping liquid from wells such as deep oil or water wells.

Another object of the invention is to provide an apparatus of the character described whereby the load of the column of liquid may be balanced, and an operating liquid utilized for the operation of the pump.

Another object of the invention is to provide an apparatus of the character described whereby gravity may be utilized to effect the down-stroke, or return-stroke, of the pump, and whereby counterbalancing equipment such as commonly used may be dispensed with, the balancing fluid being utilized as a shock absorber for retarding the down, or return stroke of the pump.

A further object is to provide a pumping apparatus of the character described whereby the pump rod will be actuated, on powerstroke, on a vertical line, thus preventing the side swinging motion of said rod, and whereby the rod, upon downward stroke, will be actuated by gravity alone and will not be forced downward by the apparatus, thus eliminating lateral or swinging movements of the rod on down-stroke.

A still further object is to provide a pumping apparatus of the character described which is of such construction that a longer stroke is possible than would be the case with pumping apparatus now commonly used.

A still further object is to provide pumping apparatus whereby the working load may be readily ascertained and regulated.

A still further object is to provide a pumping apparatus that is of very simple construction and that may be easily and inexpensively operated.

With the above and other objects in view, the invention has particular relation to certain novel features of construction, operation, and arrangement of parts, an example of which is given in this specification and illustrated in the accompanying drawings, wherein:—

Figure 1 shows a side elevation of the apparatus partly in section.

Figure 2 shows a vertical sectional view taken on the line 2—2 of Figure 1.

Figure 3 shows a plan view.

Figure 4 shows a fragmentary vertical sectional view of a controlling valve employed.

Figure 5 shows a sectional view of said valve taken at right angles to the view shown in Figure 4.

Figure 6 shows a cross-sectional view taken on the line 6—6 of Figure 2.

Fig. 7 shows an elevational view, partly in section taken on the line 7—7 of Figure 1, and

Figure 8 shows an elevational view, partly in section, and taken on the line 8—8 of Figure 1.

Referring now more particularly to the drawings wherein like numerals of reference designate similar parts in each of the figures, the numerals 1, 1, designate the side members of the supporting base, preferably formed of channel irons and at one end having the bed plate 2, all forming a suitable supporting framework. The well pipe 3, of the well to be pumped, may extend up through the bed plate 2, and working in the well is the conventional type of pump to be operated having the pump sucker rod 4, to the lower end of which the conventional traveling valve is attached in the usual way. Supported on suitable bases 5, 5, on opposite sides of the well are the outer stationary cylinders 6, 6, and the inner stationary cylinders 7, 7, the inner cylinders being preferably concentric with respect to the outer stationary cylinders 6. The upper ends of the outer cylinders 6 are inwardly thickened and internally threaded, and corresponding inner cylinders 7 are threaded through said inwardly thickened portions. The outer ends of both the cylinders 6 and 7 are closed excepting they have the respective relief ports 8 and 9.

Fitted closely over the respective stationary cylinders 6 are the traveling cylinders 10, 10, whose upper ends are closed by the respective heads 11, 11. Mounted on the heads 11 is a walking beam preferably formed of the channels 12, which are suitably bolted together and which clamp the sucker rod 4 between them.

Within the cylinders 7 there are the pistons, as 13, which are attached to the respective piston rods 14. Each piston rod 14 works through a central bearing in the outer end of the corresponding cylinder 7 and extends on through the corresponding head 11 and between the channels 12 and is threaded to receive the clamp nuts 15, 16, which clamp against the inner side of the corresponding head 11 and against the upper side of the walking beam respectively, whereby the piston rods 14, as well as the walking beam, are clamped to the respective cylinder heads 11.

The numeral 17 designates a storage tank which is mounted on the supporting channels 1, 1, and which is equipped with the pop-off valve 18, and the pressure indicator 19a. The storage tank 17 will be partly filled with an operating liquid as indicated at 18', and partly

filled with a pressure fluid such as air under pressure.

There is a pump 19, which, in the present instance, is shown operatively connected to a suitable motor 20, preferably an electric motor. There is a balanced valve mechanism comprising the cylinder 21 in which the spaced piston valves 22, 22, are fitted. These valves are fastened on to the piston rod 23 whose upper end is pivotally connected to the outer end of the lever 24. The inner end of this lever is pivotally connected to a suitable bracket 25 which is shown as being clamped around the air pump cylinder 26 herein-after referred to.

15 The lever 24 is formed with a yoke 27 which is clamped about a coil spring 28. This spring surrounds the sleeve 29, which is connected to the walking beam 12 by means of the cross bar 30. The sleeve 29 is mounted to slide on the 20 guide rod 31 whose lower end is anchored to the supporting framework. On the sleeve 29 are the spaced upper and lower collars 32, 33, which are adjustable thereon. Upon the up stroke of the pump, the lower collar 33 will 25 strike the lower end of the spring 28 and actuate the lever 24 and the valves 22 upwardly, and upon the down stroke of the pump the upper collar 32 will strike the upper end of the spring 28 and actuate the lever 24 and the valves 22 30 downwardly, said spring 28 acting as a bumper or shock absorber.

Leading out from the storage tank 17, beneath the liquid level, is the line 34 which is connected into the pump 19, and leading out from said 35 pump casing is pressure line 35 which enters the cylinder 21 of the balanced valve mechanism. Leading out from said cylinder 21 there is a pressure line 36 which has the branches 31, 37, which are connected into the lower ends of the 40 inner stationary cylinders 1. When the valves 22, 22, are in their lower position, the pressure lines 35, 36, will be in communication, as illustrated in Figure 4, and the operating liquid will be supplied to said inner stationary cylinders. 45 When the valves 22, 22, are in their upper position, the liquid flowing through the line 35 will be diverted from the line 36 and the line 35 will be placed in communication with the return line 38 which is connected into the upper end of the cylinder 21 and is also connected into the line 34 entering the casing of the pump 19. When 50 the balanced valve mechanism is in this position, that is, in the position shown in Figure 5, the liquid in the inner stationary cylinders 1 may return through the branches 31 and the pressure line 36 into the cylinder 21 beneath the lower valve 22 and thence through the relief line 38 back into the line 34. This returning liquid may enter the pump 19, the excess liquid being 55 returned into the tank 17. With the balanced valve mechanism in the position indicated, that is, in the position shown in Figure 5, the liquid being pumped by the pump 19 will flow idly through the pressure line 35, and cylinder 21, 60 and the return line 38 back to the pump.

Incorporated into the line 39 there is the valve seat 40 which may be controlled by the manually operated needle valve 41. The flow of the returning liquid to the storage tank 17 from the 65 cylinders 1, and consequently the speed of pump operation, may be controlled by this valve 41.

As hereinabove indicated, there is an air pump having the cylinder 26 in which the plunger 42 is mounted to reciprocate. This plunger is 70 attached to the plunger rod 43 which is extended

up between the walking beam channels 12 and up also through the cross-bar 30, said bar and channels being clamped between the nuts 44, 45, which are threaded on to plunger rod 43. An air pressure line 46 leads from the lower end of the pump cylinder 26 and enters the storage tank 17 above the liquid level therein. Incorporated into the pressure line there is a back pressure valve 47 and an air regulator 48. This regulator is of conventional construction and may be set to permit a predetermined pressure in the tank, the air from the pump thereafter escaping to free atmosphere through the relief valve 48a. As the walking beam 12 moves up and down, the air pump will be operated to replenish the pressure fluid in the tank 17, in case the pressure thereof should become reduced below the required pressure.

Pivots mounted on opposite sides of the head of the cylinder 21 are the upstanding arms 20 49, 49, whose upper ends are connected by a coil spring 50. Mounted on the upper ends of these arms 49 are the rollers 51, 51. On the valve rod 23 there is an accelerator head 52 whose upper end and lower ends are tapered. Upon up-stroke 25 of the pump, when the collar 33 engages the lower end of the spring 28, the lever 24 and the rod 23 will be moved upwardly, as hereinabove explained, and when the head 52, upon its upward movement, passes the centers of the rollers 30 51, the pressure of said rollers against the downwardly tapering lower end of the head will cause an accelerated upward movement of the rod 23 and the valves 22; and, reversely upon down-stroke of the pump, when the collar 32 strikes 35 the upper end of the spring 28, the lever 24 and rod 23 will be moved downwardly, and when the head 52 passes center, relative to the rollers 51, upon its downward movement, the pressure of said rollers against the upper end of the head 52 will cause an accelerated downward movement 40 of the rod 23 and the valves 22, thus causing a quick and positive movement of said valves in each direction.

Leading out from the storage tank 17 above 45 the level of the operating liquid, there is an air pressure line 53 which separates into the branches 54, 54, and said branches enter the lower ends of the stationary outer cylinders 6 through the inlet ports 55.

The operation of the apparatus is as follows:— An operating fluid, such as oil, is placed in the storage tank 17 in the required amount. The set collars 32, 33, are adjusted for the desired length of the stroke. The choke valve or needle valve 55 41 should then be partially closed. Air should then be pumped into the storage tank 17 until the outer cylinders 18 begin to rise. The apparatus is thus balanced. The pump 19 should then be started. When the pump 19 is started fluid is 60 pumped out of the tank 17. This will reduce the pressure in the tank 17 and the pumped liquid will cause the cylinders 18 to move up to upper position under the pressure of the pumped liquid. When this liquid pressure is relieved by the reverse movement of the liquid control valves, the cylinders 18 will move back down to the original position. This pump is equipped with a pressure gauge 56. The relief valve 18 should be maintained closed until the air pressure, as indicated by the gauge 18a has built up in accordance with the load pressure as indicated by the gauge 56, and the relief valve 18 should be set to open at a slightly less pressure than the maximum pressure indicated by the gauge 56. In ac- 65 70 75

tual operation, the pressure of air in the tank 17 must be somewhat less than the pressure of the operating fluid delivered from the pump 19, and indicated by the gauge 56, upon powerstroke in 5 order to insure the return of the pump rod on down stroke.

Assuming that apparatus has been adjusted as above described, upon downward stroke of the walking beam the set collar 32, upon striking the 10 absorber spring 28, will reverse the position of the lever 24, moving it and the valves 22 downwardly into the position shown in Figure 4. During this downward movement and prior to said 15 actuation of the balanced valve mechanism, the operating fluid will be returned from the inner stationary cylinders 7 through the lines 37, 36, and through the cylinder 21 and return line 39 to the pump 19 and any excess operating liquid returning through the line 34 to the tank 17. 20 When the down-stroke has effected the downward movement of the valves 22, the pressure line 35 leading from the pump 19 will be connected through the lines 36, 37, into the inner stationary cylinders 7 beneath the pistons 13 25 lifting said pistons, and the outer cylinders 10, as well as the walking beam 12 and the sucker rod 4, thus causing an up-stroke or discharge stroke of the well pump. The down stroke of the well pump will be effected by gravity, the 30 sucker rod 4 moving in approximately a straight line and the load will be cushioned, or counterbalanced by the fluid pressure in the outer cylinders 10, as well as by the resistance of the liquid beneath the pistons 13, the lower ends of the 35 cylinders 7 beneath the pistons 13, upon down-stroke, being in direct communication with the tank 17 through the pipes 37, 36, the cylinder 21, and the pipes 39 and 34.

It will be observed that the walking beam 12 moves up and down vertically so that there will be no side-swinging, or swaying of the sucker rod 4. Any loss of pressure of the pressure fluid in the storage tank 17 will be replaced, and a uniform pressure maintained, by the air pump hereinafore described, which is operated also by the walking beam 12.

The number of strokes a minute may be regulated by adjusting the choke valve 41 and this, in turn, regulates the flow of the liquid returned 50 from the inner cylinders 7 to the storage tank 17 upon down-stroke of the pump.

The drawings and description disclose what is now considered to be a preferred form of the invention by way of illustration only, while the 55 broad principle of the invention will be defined by the appended claims.

What I claim is:

1. In combination a storage tank for containing an operating liquid and a pressure fluid, a 60 reciprocable member adapted to be connected to the sucker rod of a pump in a well, means for taking the operating liquid from the tank and alternately applying the liquid to, and relieving the same from, the reciprocable member whereby 65 said sucker rod may be alternately elevated and permitted to descend by gravity, means for applying the pressure fluid from the tank to constantly tend to balance the load on the sucker rod and means operable by a reciprocable part of the apparatus for increasing the pressure of said 70 fluid in the tank.

2. Apparatus of the character described comprising a storage tank for containing an operating liquid and a pressure fluid, a reciprocable 75 member adapted to be connected to the operat-

ing rod of a pump in a well, means arranged to be actuated by said liquid to impart an upward, or power, stroke to the rod, means including a pressure pump for taking liquid from the tank and applying the same, under pressure, to said liquid-actuated means, means for by-passing all of the operating liquid from said liquid actuated means around the pressure pump into the tank to permit the rod to descend by gravity, and means for regulating the relief of the liquid to control 10 the rate of speed of such descent.

3. Apparatus of the character described comprising a storage tank for containing an operating liquid and a pressure fluid, a reciprocable member adapted to be connected to the operating 15 rod of a pump in a well, means arranged to be actuated by said liquid to impart an upward, or power, stroke to the rod, means for taking liquid from the tank and applying the same, under pressure, to said liquid-actuated means, means for relieving the operating liquid from said liquid actuated means to permit the rod to descend by gravity, means for regulating the relief of the liquid to control 20 the rate of speed of such descent, and other means for utilizing the pressure fluid 25 to retard such descent.

4. In combination an inner stationary cylinder, an outer traveling cylinder telescopically related to the inner cylinder, means on the outer cylinder for connecting the same to a pump rod, a piston 30 in the inner cylinder connected to the outer cylinder, means for alternately applying an operating liquid to, and for relieving the same from, the piston whereby the outer cylinder and pump rod connected thereto may be alternately elevated 35 and permitted to descend and other means for maintaining a substantially uniform pressure fluid in the outer cylinder.

5. In combination a pressure tank for containing an operating fluid, a reciprocable member 40 adapted to be connected to a rod of a pump in a well, a pressure conduit through which said fluid may be applied to the reciprocable member to elevate the same, a pressure pump connected to said conduit for so applying the fluid, a relief 45 conduit through which the pressure fluid may be relieved from said reciprocable member and bypassed around the pressure pump directly into the tank to permit the member to descend, a bypass return conduit, a valve mechanism controlling 50 said conduits, and automatically operable to alternately permit the application of the pressure fluid to, and relieve the same from, said member and said valve mechanism being arranged to simultaneously relieve such pressure 55 and to permit the return of the relieved pressure fluid and the pumped pressure fluid into the pressure conduit.

6. In combination a pressure tank for containing an operating fluid, a reciprocable member 60 adapted to be connected to a rod of a pump in a well, a pressure conduit through which said fluid may be applied to the reciprocable member to elevate the same, a pressure pump connected to said conduit for so applying the fluid, a relief 65 conduit through which the pressure fluid may be relieved from said reciprocable member and bypassed around the pressure pump directly into the tank to permit the member to descend, a bypass return conduit, a valve mechanism controlling 70 said conduits, and automatically operable to alternately permit the application of the pressure fluid to, and relieve the same from, said member and said valve mechanism being arranged to simultaneously relieve such pressure 75

and to permit the return of the relieved pressure fluid and the pumped pressure fluid into the pressure conduit, a valve means for manually controlling the flow of the relieved fluid through 5 said relief conduit.

7. In combination, a storage tank containing an operating liquid and a fluid under pressure, a cylinder, a piston in the cylinder connected to the sucker rod of a well pump, means including a 10 pump for taking the operating liquid from the tank and alternately applying the liquid to, and relieving the same from, the piston whereby the piston and sucker rod may be alternately elevated and permitted to descend, said means having a conduit through which all of the relieved liquid 15 may be returned, around the last mentioned pump, to the tank.

8. In combination, a storage tank containing an operating liquid and a fluid under pressure, 20 a cylinder, a piston in the cylinder, connected to the operating rod of a well pump, means including a liquid pressure generator for taking the liquid from the tank and alternately applying the liquid to and relieving the same from the 25 piston whereby the piston and rod may be alternately elevated and permitted to descend, said means having a conduit which by-passes the generator and is connected into the tank and through which the pressure in the tank may freely 30 react, through the relieved liquid, to retard the descent of the piston.

9. In combination a pressure tank for containing an operating fluid, a reciprocable mem-

ber adapted to be connected to a rod of a pump in a well, a pressure conduit through which said fluid may be applied to the reciprocable member to elevate the same, a pump connected into said conduit for so applying the fluid, a relief conduit through which the pressure fluid may be relieved from said reciprocable member and by-passed around the last mentioned pump directly into the tank to permit the member to descend, a by-pass return conduit, a valve mechanism controlling said conduits and automatically operable to alternately permit the application of pressure to and to relieve the same from said member and said valve mechanism being arranged to simultaneously relieve such pressure 15 and to permit the return of the relieved pressure fluid and the pumped pressure fluid into the tank.

10. In combination, a storage tank containing an operating liquid and a fluid under pressure, 20 a cylinder, a piston in the cylinder connected to the sucker rod of a well pump, means including a pressure pump for taking the operating liquid from the tank and alternately applying the liquid to and relieving the same from the 25 piston, whereby the piston and the load of the pump carried thereby may be alternately elevated and permitted to descend, said means having a conduit through which the relieved liquid may be by-passed around the pressure pump and 30 returned to the tank solely by the weight of the load.

LOYD E. HUTCHISON.
